CHARGE FORMING SYSTEM

Fritz Stephan, Minneapolis, Minn., assignor to
Herbert G. Benz, St. Paul, Minn.

Application December 20, 1941, Serial No. 423,772

9 Claims. (Cl. 261—37)

1

This invention relates to charge forming systems for internal combustion engines, and is particularly directed to that type of system wherein the fuel is injected by pressure into the intake manifold of the engine.

The main object of the invention is to provide a system for easily and accurately controlling the air-fuel ratio of the engine charge.

A further object of the invention is to provide a system in which the amount of fuel introduced into the engine charge is variably controlled at will.

A third object of the invention is to provide a charge forming system in which the pressure of the fuel entering the charge controls the quantity of air introduced and the air-fuel ratio of the charge, and specifically, to provide a system wherein the pressure of the fuel functions to control the quantity of air and the air fuel ratio by directly controlling the operation of the air intake throttle valve.

Another object of the invention is to operate the throttle valve controlling the air entering the charge in dependency on air pressure, and further, to operate such valve in dependency both on air pressure and fuel pressure.

A further object of the invention is to provide a variable displacement fuel pump for supplying controlled amounts of fuel to the engine charge.

Yet another object of the invention is to provide means for controlling the fluid pressure of the fuel supplied by the variable displacement pump to the engine charge.

A further object of the invention is to control the pressure of the fuel supplied to the engine charge in dependency on pressure conditions within the charge forming system.

Another object of the invention is to provide a fuel injector for introducing fuel into the engine charge under controlled pressure.

The invention will be further understood with reference to an embodiment thereof shown in the accompanying drawings, in which:

Fig. 1 is a front elevation of the charge forming system in combination with an internal combustion engine;

Fig. 2 is a sectional view of the fuel pump taken on the line 2—2 of Fig. 3;

Fig. 3 is an end elevation view of the fuel pump unit;

Fig. 4 is a sectional view of a detail of the pump unit;

Fig. 5 is an end elevation view of the cylinder unit of the pump;

2

Fig. 6 is an end elevation view of the piston assembly of the pump;

Fig. 7 is an end elevation view of the cylinder end plate unit of the pump;

Fig. 8 is a sectional view of the cylinder end plate taken on the line 8—8 of Fig. 7;

Fig. 9 is a vertical sectional view of the injector and throttle unit;

Fig. 10 is a side elevation view partly in section on the line 10—10 of Fig. 9;

Fig. 11 is a sectional view taken on the line 11—11 of Fig. 12 showing the injector unit; and,

Fig. 12 is an end view of the injector unit.

A charge forming system of the invention is adapted for use in combination with various types of internal combustion engines, including marine and aircraft as well as automotive and stationary engines. It may be employed with supercharged engines as well as with the conventional types.

In the embodiment shown in Fig. 1 the system is disclosed in combination with an engine 1 of the V type having two banks of cylinders, 2 and 3. Intake manifold 4 is provided for conducting the charge to the cylinders which in this type of engine are conventionally divided into two groups and fed by a duplicate charge forming system.

The fuel injection and throttle valve unit 5 of the invention is positioned at the anterior end of the intake manifold 4, and is supplied with fuel from pump unit 6 through fuel pipe 7.

The fuel pump unit 6 constitutes a variable displacement engine driven pump which may be controlled by the operator for the purpose of changing the charge supplied to the engine. For this purpose operating lever 69 is provided to vary the pump displacement.

The pump is of the radial type employing a plurality of cylinders, and having means for varying the stroke of the pistons.

The pump is provided with a main shaft 8 having a splined end 9 which in the embodiment shown in Fig. 1 may conveniently be gear driven from the cam shaft gear of engine 1. Conveniently the pump is constructed with frame unit 10 provided with suitable holes 11 through which it may be bolted to the engine. Cooperating with frame unit 10 is the opposite end unit 12, the same being connected by bolts 13 and clamping the cylinder assembly between the end and frame units.

In the embodiment shown the cylinders are rectangular in cross section, being formed in the cylinder unit 15 shown in Fig. 5. The end walls of the cylinders are formed by cylinder end plates

16 and 17, the latter being shown in elevation in Fig. 7.

The pistons 18 slide in cylinders 19 of the cylinder unit and conform closely to the walls of the cylinder as formed by the cylinder end plates and cylinder unit. Each piston 18 is provided with wrist pin 21 journaled therein and slotted to receive the inturned ends 22 of connecting rods 23. In the embodiment shown the connecting rods at each side of the pistons are formed in a unit, extending radially from the base members 24. The base members are pressed on the outer race 25 of the main needle bearing 26. As shown in Fig. 2, the connecting rod assembly works in recesses 27 provided in end plates 16 and 17.

The eccentric member 28 constitutes the inner race of needle bearing 26 and is adjustably mounted on main shaft 8. For this purpose main shaft 8 is provided with a squared out section 29 received in an oblong aperture 14 of eccentric member 28. The throw of eccentric member 28 is adjusted by means of cam wedge 30 which is biased to the left by spring 31 contained in bore 32 of the main shaft, as is best shown in Fig. 6. Eccentric member 28 is retained in the proper position on the main shaft by integral shoulder 33.

The position of wedge cam 30 may be adjustably controlled through push rod 34 working in bore 35 of the main shaft. The position of the push rod is controlled by the main pump operating lever 69 which is keyed to bushing 36 rotatably mounted in member 37 which is threaded into end unit 12 of the pump, being provided with a gasket 38 to provide a fluid type closure. Operating lever 69 is retained on bushing 36 by end cap 39. Bushing 36 is internally splined at 40 and slidably receives thrust member 41 which is externally splined. Thrust member 41 is externally threaded at 42 and cooperates with internal threads 43 of member 37. It will therefore be understood that on movement of operating lever 69 thrust member 40 is axially moved through rotation imparted thereto by splining 40.

Thrust member 41 is recessed to receive thrust bearing 44 which engages push rod 34 and shoulder 45 integral therewith.

The position of wedge cam 30 is therefore adjustable through variations in the axial position of push rod 34, being maintained in position against the same by spring 31. The outer portion of wedge cam 30 works in slot 46 of eccentric member 28, the cam face operating against surface 47. In this way the piston throw is suitably controlled to obtain the desired displacement of the pump.

Fuel is supplied from fuel line 48 through coupling 49 to annular recess 50 in the cylinder end plate 16. From recess 50 the fuel passes into ports 51 spaced angularly around member 16 in correspondence with the cylinders. Main shaft 8 is provided with intake valve recess 52. The fuel is received through ports 51 and is conducted by valve recesses 52 to ports 53 from which it passes through bores 54 in the frame unit 10 to ports 55 and cylinders 19.

From the cylinders the fuel passes through ports 55 of the end plate 17 through bores 56 of end unit 12, ports 53 of end plate 17 to the outlet valve recess 57 of main shaft 8. Exhaust valve recess 57 leads to an annular recess 58 in the main shaft from which the fuel passes through port 51 of end plate 17 to bore 59 in unit

12 of the pump. Thence by coupling 60 and union 61 the fuel passes to the pressure fuel line 7.

The fuel is suitably introduced from the intake valve recess 52 to the appropriate pump cylinders when the respective pistons are at the top of their stroke. As the piston recedes in the cylinder the fuel is drawn into the same until at the bottom of the stroke the movement of main shaft 8 closes the intake valve and when the piston begins its return movement the outlet valve recess 57 of main shaft 8 meets the appropriate bore 56 to permit the fuel to be forced to fuel line 7. Through the above described adjustment of eccentric member 28 the piston throw and consequently the pump displacement may be varied.

In order to prevent fuel leakage in the driven end of main shaft 8 seal 62 carried by ring 63 is threaded into the frame unit 10. Any leakage past seal 62 is retained in chamber 64 formed by member 65 which is pressed into mounting frame 10 against bushing 66. Annular chamber 64 may be drained through bore 67 and drain plug 68.

The fuel supplied to line 7 from the pump unit 6 is supplied to two injector units 70 for introducing the fuel to passages 100 of the throttle and injection unit 5 for admixture therein into a charge with air.

As shown in Fig. 11 the injector unit 70 comprises a base member 71 adapted to be bolted to the manifold through holes 72. The base member is provided with fuel chamber 73 to which the fuel is introduced through bore 74 from coupling 75 connected to fuel line 7 by union 76. The base member is provided with bore 77 and valve seat 78 leading from chamber 73 to nozzle 79 provided with bore 80. Working in bore 77 is needle valve 81 provided with longitudinal recesses 82. The needle valve 81 is controlled by a diaphragm 83 clamped between base member 71 and cap 84. Cap 84 encloses biasing spring 85 which presses needle valve 81 onto its seat.

The base member 71 is provided with seat 86 adapted to be received in a suitable aperture in intake manifold unit 5 in order that the fuel may be injected into the manifold passage. Under such conditions the needle valve 81 is controlled by biasing spring 85 and the forces exerted on diaphragm 83 by the fuel pressure in chamber 73 and the air pressure in the passage 100 which is conducted to chamber 87 through bore 88 in base member 71 and bore 89 of cap member 84.

The amount of air supplied to the engine is controlled by butterfly throttle valves 90 and 91 journaled in the passages 100 on shaft 92. Shaft 92 is mounted in unit 5 on bushings 93, 94 and 95, as shown in Fig. 9.

The butterfly valves 90 and 91 are operated through shaft 92 by gear 96 on the end thereof. Gear 96 is rotated by rack 97 as shown in Fig. 10. The fuel from line 7 is supplied by union 98 and coupling 99 through bore 101 and port 102 to cylinder 103. Cylinder 103 carries rack 97, at the upper end of which plate 105 engages biasing spring 106 which presses piston 104 downwardly in the cylinder. Spring 106 is retained by cap 107 by adjustment of which the spring tension may be selected.

Chamber 108 in which rack 97 and gear 96 work may be vented through bushing 95 to the manifold system or if desired may be vented through an aperture in cap 107 to the outside atmosphere. The position taken by the butterfly valves 90 and 91 is determined by the forces

exerted by biasing spring 106, the pressure exerted on the lower face of piston 104 by the pressure of fuel in line 7, and the air pressure exerted on the upper side of piston 104 by the air in passage 100 and/or the outside atmosphere.

The operation of the charge forming system will now be described.

It will be understood that the amount of fuel supplied to the intake manifold from pump 6 can be controlled as desired by manipulation of lever 69. In the absence of further adjustment of the operating lever the amount of fuel supplied to the engine per engine revolution is determined by the efficiency of the pump which will decrease somewhat with increasing speed. Except for this factor the fuel supplied per engine revolution is constant under these conditions.

When it is desired to increase the engine output operating lever 69 may be adjusted to increase the delivery of the pump to supply a heavier fuel charge. Therefore the amount of fuel supplied to the engine may be delicately and accurately adjusted to the desired amount.

In order to obtain the correct air-fuel ratio the air intake butterfly valve is basically controlled in dependency on the amount of fuel being delivered to the engine by the fuel pump. This control is obtained through variations in the fuel line pressure caused by operation of the injector mechanism. As above described, the needle valve 81 is spring biased to closed position, and is raised off its seat by the pressure developed against diaphragm 83. Assuming an increasing delivery by the pump through operation of lever 69, fuel will be supplied to chamber 73 of the injector at an increasing rate, and the pressure therein will rise until the force is exerted in opposite directions on the needle valve by diaphragm 83 and spring 85 come into equilibrium, the increased rate of fuel supply being accommodated by the further opening of the needle valve.

Through the mechanism of the injector, therefore, the pressure in the fuel line is varied in accordance with the rate of delivery of the pump. This pressure is also delivered, as explained above, to the cylinder 103 where it acts on piston 104 to control the position of the throttle valve. The position taken by piston 104 through which the throttle valve is controlled is determined by the force exerted thereon by the fuel pressure and by the opposing biasing force exerted by spring 106. The size of piston 104 and the associated mechanism is suitably designed in accordance with the desired range of operating fuel pressures to actuate the throttle valve in cooperation with the biasing spring, as desired. Final adjustment after installation is attained by varying the compression on the biasing spring through cap 107.

Through the above described features of operation the amount of air supplied to the engine is controlled in accordance with the pressure of the fuel actually injected into the engine charge, and consequently it is possible to obtain the desired air fuel ratio over the necessary range of operating engine speeds.

The charge forming system further compensates for variations in atmospheric pressure such as may be caused by variations in altitude or otherwise. Thus, a decrease in atmospheric pressure is directly communicated to chamber 108 on the upper side of the throttle-actuating piston 104. Consequently the decreasing atmospheric pressure permits the piston to rise further and therefore to open the throttle valve in order to permit an increased amount of air to be supplied

to the engine. This effect compensates for the decreased weight per unit volume of air resulting from the decreased atmospheric pressure.

Whereas in the construction shown chamber 108 is vented to the atmosphere and also to the passage 100 inside of the throttle valve, if desired it may be vented only to the atmosphere, or only to the passage inside the throttle valve. In case a supercharger is employed chamber 108 may, if desired, be vented to the charge forming system between the supercharger and the throttle valve, this connection producing an equivalent effect to that produced by venting chamber 108 to the atmosphere when a supercharger is not employed.

It will be understood that the relative effects produced on the throttle valve by the fuel pressure and air pressure in chamber 108 may be varied over a wider range through the employment of differential pistons, or if desired, by diaphragms of differing area operated on by the fuel and air pressures.

In the embodiment shown the compensating effect is limited by the force produced on the outside of diaphragm 83 controlling needle valve 81 by the pressure admitted thereto through bores 88 and 89. By this construction the air pressure of the charge in passage 100 produces a further effect on the position of the throttle valve by superimposing a variation on the fuel pressure in addition to that effected in dependency on the delivery of the pump.

The pressure communicated from the charge forming system through bores 88 and 89 to chamber 87 acts directly against the force exerted on diaphragm 83 by the fuel pressure. Assuming a drop in the pressure of the charge in passage 100, chamber 87 is correspondingly evacuated and, in dependency on the force thereby withdrawn from diaphragm 83, needle valve 81 is opened to lower the fuel pressure until the forces exerted on the needle valve by the diaphragm and spring 85 are again in equilibrium.

The consequent reduction in fuel pressure in line 7 is communicated to piston 104 controlling the position of the throttle valve. This pressure reduction tends to permit the throttle valve to close under the operation of biasing spring 106. It will therefore be understood that the compensation for atmospheric pressure variations produced by the action of piston 104 in dependency on the air pressure in chamber 108 is limited by the reverse effects of the fuel pressure variations in cylinder 103 resulting from variations in the pressure of the charge in passage 100. It will of course be understood that the pressure of the charge in passage 100, while responsive to other factors including engine speed and throttle valve position, is also dependent upon atmospheric pressure.

Under certain circumstances particularly in aircraft engines which are most efficiently operated at full throttle, the opposing effects may preferably be substantially balanced so that, when the engine is so operating, variations in positions of operating lever 69 serve to obtain a fine adjustment of the air fuel ratio to obtain optimum engine efficiency.

It is clear that within the scope of the invention the relative effects of pressure of the charge in passage 100 and air pressure in chamber 108 on piston 104 may be varied as desired by selecting the dimensions of piston 104 and diaphragm 83, or by employing differential pistons or diaphragms for either of these elements.

Further details of the operation of the charge forming system may be explained in connection with the situation where the engine is operating and receives an increased load without adjustment of operating lever 69. Under these circumstances the engine will lose speed, and consequently the pressure in passage 100 will increase due to the fact that less air is demanded by the engine. The resulting increase in pressure in passage 100 is communicated to diaphragm 83 and increases the force acting to close the needle valve. This in turn tends to increase the fuel pressure, which would result in causing piston 104 to close the throttle valve slightly.

Because, however, the pump delivery is decreased as a consequence of the decreasing engine speed the effect of the increased pressure in passage 100 to increase the fuel pressure is opposed, and consequently the throttle valve does not act solely in response to the variation in pressure in passage 100.

Obviously, the dimensions of diaphragm 83 may be selected to obtain a predominating effect by either of these two factors. However, in most cases it is preferable to have the increasing pressure in passage 100 resulting from decreasing engine speed exactly counterbalanced so far as its effect on the fuel pressure is concerned by the corresponding drop in fuel pressure with decreasing pump delivery.

I claim:

1. A charge forming system for an internal combustion engine comprising means defining a charge forming chamber and an air intake delivering to the chamber, a manual control, a fuel nozzle discharging into said chamber, a fuel pump means having a variable delivery controlled by said manual control to deliver fuel to said fuel nozzle at a varying rate independently of pump operating speed, an automatic throttle valve controlling delivery of air to the charge forming chamber at a variable rate, spring means biasing said air throttle valve to closed position, and means independent of the manual control and responsive to the pressure of fuel delivery to the fuel nozzle to control the position of the air throttle valve.

2. A charge forming system for an internal combustion engine comprising means defining a charge forming chamber and an air intake delivering to the chamber, a manual control, a fuel nozzle discharging into such chamber, fuel pump means having a variable delivery controlled by said manual control to deliver fuel to said fuel nozzle at a varying rate independently of pump operating speed, automatic pressure responsive fuel valve means between the pump and the nozzle for regulating the pressure of the fuel delivered by the pump to the nozzle, spring means biasing said fuel valve to closed position and means responsive to the fuel delivery to the valve for opening the valve, an automatic throttle valve controlling delivery of air to the charge forming chamber at a variable rate, and means independent of the manual control and responsive to the pressure of fuel delivery to the automatic fuel valve in opposition to said spring means to control the position of the air throttle valve.

3. A charge forming system for an internal combustion engine comprising means defining a charge forming chamber and an air intake delivering to the chamber, a manual control, a fuel nozzle discharging into such chamber, fuel pump means having a variable delivery controlled by said manual control to deliver fuel to said fuel

nozzle at a varying rate independently of pump operating speed, automatic pressure responsive fuel valve means between the pump and the nozzle for regulating the pressure of the fuel delivered by the pump to the nozzle, spring means biasing said fuel valve to closed position and means responsive to the fuel delivery to the valve for opening the valve, an automatic throttle valve controlling delivery of air to the charge forming chamber at a variable rate, spring means biasing said air throttle valve to closed position, and means independent of the manual control and responsive to the pressure of fuel delivery to the automatic fuel valve to control the position of the air throttle valve.

4. A charge forming system for an internal combustion engine comprising means defining a charge forming chamber and an air intake delivering to the chamber, a manual control, a fuel nozzle discharging into such chamber, a fuel pump having a variable displacement controlled by said manual control to deliver fuel to said fuel nozzle at a varying rate independently of pump operating speed, automatic pressure responsive fuel valve means between the pump and the nozzle for regulating the pressure of the fuel delivered by the pump to the nozzle and operative independently of the manual control in response to the fuel delivery and the air delivery pressure, an automatic throttle valve controlling delivery of air to the charge forming chamber at a variable rate, and means independent of the manual control and responsive to the fuel delivery to control the position of the air throttle valve.

5. A charge forming system for an internal combustion engine comprising means defining a charge forming chamber and an air intake delivering to the chamber, a manual control, a fuel pump having a variable displacement controlled by said manual control to deliver fuel to said fuel nozzle at a varying rate independently of pump operating speed, automatic pressure responsive fuel valve means between the pump and the nozzle for regulating the pressure of the fuel delivered by the pump to the nozzle and operative independently of the manual control in response to the fuel delivery and the air delivery pressure, spring means biasing said fuel valve towards closed position in opposition to the fuel delivery pressure, an automatic throttle valve controlling delivery of air to the charge forming chamber at a variable rate, and means independent of the manual control and responsive to the fuel delivery to control the position of the air throttle valve.

6. A charge forming system for an internal combustion engine comprising means defining a charge forming chamber and an air intake delivering to the chamber, a manual control, a fuel nozzle discharging into said chamber, fuel pump means adapted to deliver fuel to the fuel nozzle at a variable rate independently of pump operating speed and fuel regulating means controlled by said manual control to vary the fuel delivery rate from the pump to the fuel nozzle, automatic pressure responsive fuel valve means between the pump and the nozzle for regulating the pressure of the fuel delivered by the pump to the nozzle and operative independently of the manual control in response to the fuel delivery and the air delivery pressure, an automatic throttle valve controlling delivery of air to the charge forming chamber at a variable rate, and means independent of the manual control and responsive to the pressure of fuel delivery to the auto-

matic fuel valve and the air delivery pressure to control the position of the air throttle valve.

7. A charge forming system for an internal combustion engine comprising means defining a charge forming chamber, a manual control, a fuel nozzle discharging into such chamber, fuel pump means adapted to deliver fuel to the fuel nozzle at a variable rate independently of pump operating speed and fuel regulating means controlled by said manual control to vary the fuel delivery rate from the pump to the fuel nozzle, automatic pressure responsive fuel valve between the pump means and fuel nozzle for regulating the pressure of the fuel delivered by the pump to the nozzle and operative independently of the manual control in response to fuel delivery pressure and air delivery pressure, spring means biasing said fuel valve toward closed position in opposition to the fuel delivery pressure, an air throttle valve entirely automatic in operation controlling the delivery of air to the charge forming means at a variable rate, means responsive to fuel delivery pressure and air delivery pressure to control the position of the air throttle valve, and spring means biasing said air throttle valve toward closed position in opposition to the fuel delivery pressure.

8. A charge forming system for an internal combustion engine comprising means defining a charge forming chamber and an air intake delivering to the chamber, a manual control, a fuel

30

nozzle discharging into said chamber, a fuel pump means having a variable delivery controlled by said manual control to deliver fuel to said fuel nozzle at a varying rate independently of pump operating speed, an automatic throttle valve controlling delivery of air to the charge forming chamber at a variable rate, and means independent of the manual control and responsive to the pressure of fuel delivery to the fuel nozzle to control the position of the throttle valve.

9. A charge forming system for an internal combustion engine comprising means defining a charge forming chamber and an air intake delivering to the chamber, a manual control, a fuel nozzle discharging into said chamber, fuel pump means having a variable delivery controlled by said manual control to deliver fuel to said fuel nozzle at a varying rate independently of pump operating speed, automatic pressure responsive fuel valve means between the pump and the nozzle for regulating the pressure of the fuel delivered by the pump to the nozzle and operative independently of the manual control in response to the fuel delivery, an automatic throttle valve controlling delivery of air to the charge forming chamber at a variable rate, and means independent of the manual control and responsive to the pressure of fuel delivery to the fuel nozzle to control the position of the throttle valve.

FRITZ STEPHAN.
